VENDING MACHINE

John C. Gurath and Philip Machut, Chicago, Ill.

Application June 22, 1932. Serial No. 618,762

6 Claims. (Cl. 312—63)

This invention relates to certain novel improvements in vending machines, and has for its principal object the provision of an improved construction of this character which will be 5 highly efficient in use and economical in manufacture.

It is an object of this invention to provide an improved article-vending machine.

It is another object of the invention to provide 10 an improved coin-controlled article vending machine.

Other objects will appear hereinafter.

The invention consists of the novel combination and arrangement of parts to be hereinafter 15 described and claimed.

The invention will be best understood by reference to the accompanying drawings, showing the preferred form of construction and in which:

Fig. 1 is a front elevational view of a preferred form of the invention with a part of the cabinet broken away;

Fig. 2 is a vertical sectional view on line 2—2 in Fig. 1;

Fig. 3 is a horizontal sectional view on line 25 3—3 in Fig. 2;

Fig. 4 is a fragmentary sectional view on line 4—4 in Fig. 2;

Fig. 5 is a sectional view on line 5—5 of Fig. 3;

Fig. 6 is a sectional view on line 6—6 of Fig. 30 4; and

Fig. 7 is a side elevational view of the coin control embodied in the invention.

In the preferred form of the invention shown 35 in the drawings 10 generally indicates a cabinet or casing within which may be arranged one or more article-storage magazines 11 adapted to receive articles 13 through their upper ends 12. The bottom of each magazine 11 is provided by a tiltable dispensing member 14. Each of these 40 tiltable dispensing members 14 is pivotally mounted at 15 on the corresponding magazine 11.

Each dispensing member 14 includes an upper inclined article-supporting shelf 19 and a lower, 45 normally horizontal element 16 therebelow. Each element 16 is provided with slots 17 and through each of these slots 17 projects an article ejecting finger 18. These ejecting fingers 18 project above the element 16 of the dispensing member 14 and along side the article-supporting shelf 19.

Each article-supporting shelf 19 has its upper end 70 bearing on an inclined upper end portion 50 of a bracket 41 that is attached to the rear wall of cabinet 10, and each shelf 19 has an angled lower end (Fig. 5) which is projected through a slot in the corresponding element 16. The shelf

19 and element 16 of each dispensing unit 14 are urged toward each other by a spring 73.

The ejecting fingers 18 are arranged in pairs and each pair of the same is formed as part of an ejecting member 74 that is pivotally mounted 60 on a shaft 20 arranged below the corresponding magazine 11. Adapted to engage each ejecting member 18 to urge the same (counterclockwise Fig. 2) against the action of a spring 21 is a pivotal lever 22. These levers 22 and the shafts 65 20 are mounted on brackets 41 suspended from the magazines 11.

Formed on the front end of each dispensing member 14 is a depending flange or apron 23 and projecting laterally or horizontally forwardly 70 from each of these aprons 23 is an ear or lug 24.

Extending horizontally across the cabinet 10 in front of the magazines 11 is a coin-controlled rock shaft 25 on which is a hand knob 26. Mounted on the shaft 25 are spaced cams 27. A coin control device, (Figs. 5 and 7), to be described hereinafter, is associated with the rock shaft 25, and when a suitable coin is inserted into the coin chute 46 the shaft 25 may be rocked (clockwise Fig. 2) causing a cam 27 to bear on the ear portion 24 of one of the tiltable dispensing members 14, thereby tilting the same dispensing member 14 (counterclockwise Fig. 2). As the dispensing member 14 is thus tilted the depending apron 23 thereof engages the corresponding pivotal lever 22 therebelow and the lever 22 is thereby rocked (counterclockwise Fig. 2) into engagement with the member 74; causing the ejecting fingers 18 of member 74 to move (counterclockwise Fig. 2) in the slots 17, while, at the same time, the inclined article-supporting shelf portion 19 of the actuated dispensing member 14 is being tilted (counterclockwise Fig. 2). The ejecting fingers 18 thus engage the lowermost article 13 in the stack of the same in the magazine 11 and eject the lowermost article 13 off the inclined shelf 19 onto the inclined dispensing chute 28 which opens to the exterior of the cabinet 10 through a slot 42.

Pivots attached to each tiltable dispensing member 14, at 29, is a lever 30 which has a horizontally extending angled upper end portion 31. This portion 31 rides the inclined face 32 of a member 33, one of which is pivotally mounted at 43 on the front of each magazine 11. Each member 33 has a horizontally angled end 34 which is adapted to be projected into the magazine 11 below the bottom of the front wall thereof and above the inclined shelf 19. As the tiltable dispensing member 14 and its apron 23 are tilted counterclockwise (Fig. 2), by engagement of a cam 27 on 100 105 110

rock shaft 25 with a corresponding portion 24, the member 30 is depressed, against the action of a spring 35, and the angled end portion 31 of member 30 rides down the inclined face 32 of member 5 33, thereby rocking member 33 counterclockwise, Fig. 2, and urging the horizontally extending angled lower end portion 34 of the latter into the magazine 11 above the lowermost article 13 in the stack, thus supporting the stack of articles in 10 the magazine while the lowermost article 13 thereof is being dispensed onto the chute 28.

Pivotedly mounted at 36 on each magazine 11 is a latch member 37 which works in a guide 38. Each guide 38 has a portion 40 that is secured 15 to the magazine 11 and each member 37 has a latching head 39 that is adapted to engage this portion 40 if an unauthorized attempt is made to insert a tool through dispensing outlet 42, above the chute 28, to depress a dispensing member 20 14. Each latching member 37 includes an arm 41 which has an angled end portion 44. When the rock shaft 25 is rocked clockwise (Fig. 4) during the article dispensing operation, as hereinbefore described, a cam 27 on the rock 25 shaft 25 engages and presses down on the angled end portion 44 of one of the latching members 37, thereby pivoting the said latching member 37 counterclockwise (Fig. 2) at 36 and disengaging the latching head 39 thereof from the portion 40 of guide 38.

The cams 27 are so arranged on rock shaft 25 relative to each other that only one cam and one dispensing unit 14 are operated at each movement of rock shaft 25; that is the shaft 25 is always rocked clockwise (Fig. 2) and by reason 35 of the arrangement of the cams 27 the articles 13 are dispensed alternately first from one magazine 11 and then from the other so that both or all magazines may be emptied before the cabinet 40 need be opened to refill the magazines.

The members 30 are returned to ineffective position (Fig. 2) by the springs 35 and when in this position the angled upper end portions 31 of members 30 abut adjustable stops 45, one of which 45 is carried by each member 32.

The coin chute 46 is supported by the wall 48 of the cabinet 10. A magnet 49 is arranged at the bottom of the chute 46 to attract slugs and slidably mounted on one arm of the magnet 49 is 50 a sleeve 50. Pivotedly connected at 51 to the sleeve 50 is a link 52 which in turn is pivotedly connected at 53 to a lever 54 that is pivotedly mounted at 55 on wall 48. At its lower end this lever 54 has an angled end portion 56 which is 55 adapted to be successively engaged by the arms of a spider 57 that is fast on the rock shaft 25 (Figs. 5 and 7).

Mounted on wall 48 is a channeled guideway 58 in which is slidable a bar 59 that carries a pin 60. The pin 60 is adapted to be successively engaged by the arms of the spider 57. Provided in the bar 59 is a coin-receiving notch 63. Having one end pivotedly mounted at 61 on the wall 48 is a stop lever 62, the other end 64 of which is 65 aligned with the pin 60. If rock shaft 25 is urged counterclockwise (Fig. 7) when no coin is inserted into chute 46 one of the arms of the spider 57 engages the pin 60 and slides the bar 59 to the left (Fig. 7) thereby abutting the pin 60 against 70 the end 64 of lever 62 and thus preventing further movement of shaft 25. When a coin 66 is inserted into chute 46, however, the coin falls into the notch 63 in slide bar 59 and abuts a laterally extending ear 65 formed on lever 62 so that 75 when the shaft 25 is rocked (counterclockwise

Fig. 7) one of the arms of the spider 57 engages the pin 60 and slides the bar 59 and coin 66 to the left (Fig. 7); thereby forcing the coin 66 under the ear 65 of lever 62 and raising the lever 62 which is thus pivoted counterclockwise, Fig. 7. 80 The coin 66 is thus discharged from the notch 63 in slide bar 59 into a receptacle 67 and at the same time one of the cams 27 on the rock shaft 25 engages parts 24 and 44 and operates a dispensing unit 14 in the manner hereinbefore described. 85

Should a slug be inserted into the coin chute 46 it will be held by the magnet 49. The slug is dislodged from the magnet by action of the sleeve 50 when the rock shaft is urged counterclockwise, 90 Fig. 7; this movement of rock shaft 25 causing one of the arms of the spider 57 to abut the angled end 56 of lever 54 which is thereby pivoted counterclockwise, Fig. 7. This movement of lever 54 slides the link 52 and sleeve 50 to the left (Fig. 7) and the sleeve 50 dislodges the slug from the magnet 49. 95

Pivotedly mounted on the wall 48 of the cabinet 10 is a spring-urged dog 68 which rides the teeth of a ratchet 69 on the shaft 25 to prevent 100 clockwise movement of the rock shaft 25 and cams 27.

While we have illustrated and described the preferred form of construction for carrying our invention into effect, this is capable of variation 105 and modification, without departing from the spirit of the invention. We, therefore, do not wish to be limited to the precise details of construction set forth, but desire to avail ourselves of such variations and modifications as come within the 110 scope of the appended claims.

Having thus described our invention what we claim as new and desire to protect by Letters Patent is:

1. A vending machine comprising an article-storage magazine, a tiltable article-dispensing unit at the bottom of said magazine, said unit comprising an inclined article supporting shelf and a normally horizontal element below said shelf provided with slots, a pivotal ejecting member arranged below said unit and including article-ejecting fingers having portions projecting upwardly through said slots alongside said shelf, a pivotally mounted lever having an end portion adapted to bear against and pivot said ejecting member, said element having a depending portion adapted to be depressed into engagement with the other end of said lever, a laterally extending lug on said element, a rock shaft, and a cam on said rock shaft adapted to engage said 115 lug to tilt said dispensing unit and pivot said ejecting member.

2. A vending machine comprising an article-storage magazine, a tiltable dispensing unit at the bottom of said magazine including an inclined 135 article-supporting shelf and an element below said shelf provided with slots, a pivotal ejecting member arranged below said element including article-ejecting fingers having portions projecting upwardly through said slots alongside said shelf, a pivotal lever having an end portion adapted to bear against and pivot said ejecting member, and means for operating said unit and ejecting member including a rock shaft and a cam thereon adapted to engage said element and 140 tilt the same into engagement with the other end portion of said lever.

3. A vending machine comprising an article-storage magazine, a tiltable dispensing unit at the bottom of said magazine including an in- 145

- clined article-supporting shelf, a pivotal ejecting member arranged below said shelf and including article-ejecting fingers having portions projecting upwardly alongside said shelf, a pivotal lever having an end portion adapted to bear against and pivot said ejecting member, and means for operating said dispensing unit and ejecting member including a rock shaft and a cam thereon adapted to engage said dispensing unit and tilt a portion thereof into engagement with the other end portion of said lever. 5 to engage said dispensing unit and tilt a portion thereof into engagement with the other end portion of said lever. 10 80
4. A vending machine comprising an article-storage magazine, a tiltable dispensing unit at the bottom of said magazine including an inclined article-supporting shelf, a pivotal ejecting member below said shelf including article-ejecting fingers having portions projecting upwardly alongside said shelf, a pivotal lever having an end portion adapted to bear against and pivot said ejecting member, a member pivotally mounted on the magazine having an inclined face and having an angled lower end portion adapted to project into the magazine above the lowermost article during the dispensing operation, a member having pivotal connection at its lower end with said unit and having an angled upper end adapted to ride said inclined face, and operating means including a rock shaft and a cam thereon adapted 15 85
5. A vending machine comprising an article-storage magazine, a tiltable article-dispensing unit at the bottom of said magazine including an inclined article-supporting shelf, a pivotal ejecting member including article-ejecting fingers having portions movable alongside said shelf, a pivotal lever operable by said dispensing unit to operate said ejecting member, and means for operating said dispensing unit. 90
6. An article-vending machine, comprising an article-storage magazine, a tiltable article-dispensing unit at the bottom of said magazine including an inclined article-supporting shelf, a pivotal ejecting member including article-ejecting fingers having portions movable alongside said shelf, a pivotal lever operable by said dispensing unit to operate said ejecting member, a member operable by said dispensing unit having an angled end portion movable into said magazine above the lowermost article on said shelf during the dispensing operation, and means for operating said dispensing unit. 95 100
